UNITED STATES PATENT OFFICE.

FRANK H. LEHMAN, OF LEBANON, PENNSYLVANIA.

ASH-SIFTING DEVICE.

1,401,543.

Specification of Letters Patent. Patented Dec. 27, 1921.

Application filed April 6, 1920. Serial No. 371,696.

To all whom it may concern:

Be it known that I, FRANK H. LEHMAN, a citizen of the United States, residing in the city of Lebanon, county of Lebanon, and 5 State of Pennsylvania, have invented certain new and useful Improvements in Ash-Sifting Devices, of which the following is a specification.

My invention relates to improvements in 10 ash sifting devices, and more especially to those adapted to be used in the household for sifting ashes drawn from stoves and furnaces; and the invention has for its principal object the production of an improved 15 and novel sifter of this kind which may be employed in immediate conjunction with an ash can of the conventional cylindrical type, for deposition therein of the sifted ashes.

Another object of the invention is the 20 production of an ash sifter of this type, comprising a portable sifting element in the form of a bucket or container wherein ashes may be conveniently deposited directly from the ash pit, and which may then, without 25 danger of spilling the ashes, be carried to the ash can and there mounted over the can and used as a rotary sifter, thus obviating the dust, annoyance and inconvenience incident to pouring the ashes from a bucket into 30 a separate and stationary sifter and again withdrawing the same therefrom.

Another object of the invention is to provide an improved sifter of this kind, involving the use of a rotary sifting element over 35 an ash can, which requires no openings in the superposed hood or housing inclosing the sifter, either for the introduction of the ashes or the withdrawal of the cinders, and which is, therefore, substantially dust proof.

40 Another object is to provide novel and improved means for quickly and easily mounting the sifting element for rotary movement in the hood.

Another object is to provide an improved 45 detachable hinged connecting and supporting member between the can and the hood, whereby the latter is enabled to be swung back and supported in appropriate position to permit the convenient introduction and 50 mounting of the sifting element therein, while at the same time remaining capable of being lifted and removed from the can without the necessity of disconnecting or undoing any of the parts.

55 A further object of the invention is to provide improved rotary means in connec-

tion with an ash sifter of this type which will produce an intermittent jarring or shocking movement, whereby to promote and facilitate the sifting process, and to 60 cause the dislodgment of particles of dust which may settle on such parts as it may be necessary for the operator to touch or which he may otherwise come into contact with in the manipulation of the device, and thereby 65 to clean the same.

With the above and other objects in view, the nature of which will more fully appear as the description proceeds, the invention consists in the novel construction, combination and arrangement of parts as herein 70 fully described, illustrated and claimed.

In the accompanying drawings, forming part of the application, similar characters of reference indicate corresponding parts in all 75 the views.

Figure 1 is a central vertical sectional view of an embodiment of my invention, showing the portable ash container mounted in position for rotation in the hood. 80

Fig. 2 is a similar view showing the hood swung back at right angles to the can and with the ash container removed therefrom.

Fig. 3 is a bottom plan view of the hood.

Fig. 4 is a perspective view of the hood 85 shown as removed from the ash can.

Fig. 5 is a fragmentary view taken on line 5—5 of Fig. 1.

Fig. 6 is an elevation of the preferred embodiment of the portable container; and 90 Fig. 7 is an elevation of a modified form of the container.

Referring more particularly to the drawings, 1 indicates the preferred embodiment of my improved portable ash container and 95 sifter, which is constructed substantially in the form of a bucket open at the top and having side walls 2 preferably cylindrical in form, a bottom 3, and a bail 4 secured to the side walls in the ordinary manner as by 100 perforated ears 5. The side walls 2 differ from those of the ordinary bucket in that the same are made of foraminous or reticulated material, such as perforated sheet metal or wire mesh, and are thus adapted to function as a sifting medium when the device is mounted and operated in the manner hereinafter described. The bottom 3 of the container is made of imperforate material and is secured to the side walls at their lower 105 edges as shown at 6, Fig. 6. Surrounding the side walls 2 are auxiliary walls 7, pref-

erably in the form of frusto-cone shaped shells, secured at their lower edges to the outer face of the side walls as at 8, and diverging outwardly and upwardly toward 5 the top of the container, the upper edges 9 of said auxiliary walls being thus spaced a substantial distance from the side walls 2. These auxiliary walls are also made of imperforate material, and thus form in effect 10 auxiliary container means adapted to catch such particles of the ashes as pass through the openings or meshes of the side walls 2. Ordinarily the container will be used as a receptacle for depositing and carrying ashes 15 in the same manner as a common bucket, being either placed on the floor or ground in substantially vertical upright position or carried in such position by means of the bail 4, and when so used, it will be apparent, 20 that the auxiliary walls 7 will act to retain all ashes dropping therein through the side walls and will effectively protect the container against the scattering of ashes therefrom on the floor. In practice it has been 25 found that when the container is thus used as a receptacle, only a comparatively small portion of the ashes percolates through the side walls, even when the container is entirely filled and when it is subjected to severe 30 jars and shocks such as might tend to thoroughly settle the contents, and it has further been found that a series of two or more of such auxiliary walls, one disposed above the other about the side walls, the lowermost 35 having its lower edge adjacent the bottom 3, will most efficiently meet the requirements of the invention, inasmuch as such an arrangement admits of relatively wide divergence of the walls and thus tends to facilitate 40 the ejection of the ashes when the container is used as a sifting element, without adding undue width thereto or rendering the same bulky or inconvenient to handle. I have accordingly adopted this construction 45 as the preferred form of the container, as clearly shown in Fig. 6, although it will be understood that a container having a single auxiliary wall, as shown in the modified form, Fig. 7, or one having a plurality of 50 such walls, or walls of different contour and conformation, falls within the scope of the invention as covered by the appended claims.

This invention contemplates the employment of a portable container thus constructed 55 in the capacity of a rotary sieving element for separating the ashes deposited therein by retaining the valuable unconsumed portions thereof in the body of the container, and dropping and ejecting the finer consumed portions through the openings in the side walls; and the means preferably adopted for thus employing the container comprise, a cylindrical hood 10 adapted to be removably seated on an ash can 60 of the conventional cylindrical type, said hood having imperforate side walls 11, and a closed top 12, and being internally provided with an inwardly extending peripheral flange 13 offset above its lower edge for engaging the upper edge 14 of the can, the 65 joint between the hood and the can being thus made close and substantially dust proof. Journaled in a relatively wide and firm bearing, preferably in the form of a U shaped bracket 16 disposed within the hood 70 adjacent one of the side walls thereof, and passing through suitable bearing openings in both of the legs 20 and 21 of said bracket, is a short shaft 17, which extends outwardly 75 through an opening in the adjacent side wall coinciding with said bearing openings, and which is provided externally of the hood with a crank, 18, whereby it is adapted to be rotated. This shaft is held in operative position and secured against lateral displacement in the bearing by a collar 19 disposed thereon between the legs of the bracket and held in place by a pin 22. The shaft extends within the hood an appreciable distance beyond the bearing and carries at its 80 inner end a coupling member 23 of appropriate form to engage a suitable coöperating coupling member 24, provided in the bottom 85 3 of the ash container. Opposite the shaft within the hood and at a distance from the 90 inner end thereof sufficient to permit the insertion of the container, is disposed a head or cover 25, preferably provided with a flanged rim 26 of slightly larger diameter than the container so as to freely receive the 95 upper end portion thereof and thus act as a closure and support therefor. Said head is 100 rotatively mounted on a pivot 27, which extends toward the shaft and is in axial alignment therewith, and said pivot is in turn 105 carried by an arm 28, hingedly depending from the top of the hood and arranged for radial movement in a vertical plane coinciding with the axis of the shaft. Thus, as will be seen, the head 25 is adapted to be swung 110 to and fro and moved into and out of engagement with the container at the will of the operator, whereby when the container is longitudinally inserted between the shaft and the head, it may by a single movement 115 of the latter be at once securely closed and operatively supported for rotary movement on a horizontal axis over the ash can.

Preferably the arm 28 is formed with an eye 31 at its upper end, and is secured to the 120 top of the head by a bracket 30 having downwardly extending ears 29 spaced apart to receive the eye between them, a hinge pin 32 passing through the eye and extending through suitable perforations in the ears. 125 For securely retaining the head in closed and supporting relationship with the container, a spring pressed detent 46 is provided, which is adapted to enter a suitable notch or recess 47 formed in the outer periphery of the eye 130

31, a similar notch or recess 48 being formed at another point on the eye to receive the detent and hold the head in its extreme remote or open position. To obviate the necessity 5 of having any objectionable openings in the head wherethrough ashes from the container might exude, the head is preferably mounted on the pivot by means of a dished hub 33, in the form of a boss centrally disposed 10 to the outer face of the head, said hub having a central bearing opening for the reception of the pivot, and the pivot being operatively secured thereto by means of a horizontal cross pin 34 passing through the pivot 15 and projecting from either side thereof within the hub. A sleeve 35, pinned to the pivot adjacent the hub, is provided to receive the thrust of the head and limit its lateral movement. With this construction, it will be 20 noted, that by proper relative arrangement of the sleeve and cross pin and by making the opening in the hub of a diameter slightly larger than that of the pivot, the head 25 may be given sufficient lateral and angular 25 play to admit of its easy reception of the upper end of the container when moved into engagement therewith.

To avoid spilling the ashes, it is essential 30 that the container, while being introduced and mounted in the hood, be held and maintained in substantially upright vertical position and that suitable means be provided to enable the container to be introduced in this position. To meet this requirement, the hood is detachably hinged 35 to the can, and a support is provided whereon the hood, when swung back on the hinge, is adapted to rest in a position substantially at right angles to the can, thus 40 bringing the shaft 17 into vertical axial position with the head 25 vertically above the same. Preferably the hinge and support are made integral and are produced from a single piece of rod material as 36, 45 bent up into suitable shape to form, spaced hook members 37 adapted to be detachably received over the upper edge of the can, horizontal trunnion members 38 proceeding outwardly and oppositely from the shanks 39 of the hook members and passing through 50 perforated ears 40 extending downwardly from the lower edge of the hood, and a bridge member 41, uniting said trunnion members and projecting outwardly to form the support. It will be observed that the hinge and 55 support are thus carried by the hood and are unitary therewith, whereby the hood may be readily detached and removed from the can by simply lifting it vertically a slight 60 distance above the upper edge of the can, as by means of the hand grip 42, and it is apparent that when the hood is thus removed, there is nothing to prevent or hinder the can being emptied and otherwise 65 handled in the usual manner.

In the preferred embodiment of the device here shown, the coupling member 23 on the end of shaft 17 is made rectangular in cross section and is tapered rearwardly on the side facing the bearing and reversely tapered on its opposite or forward side. The coupling member 24, secured to the bottom of the container, is in the form of a rectangular box, (see Fig. 5), having a closed imperforate top wall 43, and imperforate side walls 44 of somewhat greater length than the sides of the coupling member 23, and the same is provided with a bottom wall 45 having a circular opening therein of appropriate size to freely receive 80 the member 23. Thus, while the member 23, owing to its tapered character, will be readily received into the member 24, and may be easily withdrawn therefrom when the container is lowered and raised vertically on the shaft, the bottom wall of the member 24 will effectually act as a retaining flange to prevent disconnection of the shaft and container when the container and shaft are brought to horizontal axial position as 90 by returning the hood to its seated position over the can.

In operation, the container is placed in a convenient position adjacent a stove or furnace and there filled with ashes from the 95 ash pit in the usual manner, the portion of the ashes escaping through the side walls being caught and retained by the auxiliary walls as hereinbefore explained. When thus filled the container may be taken up 100 by the bail and carried to the ash can in the same manner as an ordinary bucket without danger of spilling or dropping the ashes on the floor. The hood 10 is now swung back on the hinge until it rests on 105 the support 41, when the container is introduced therein and placed upright on the shaft, with the coupling member 23 in internal engagement with the coupling member 24. The head 25 is then drawn down into 110 closed position over the mouth of the container, where it will be securely held by the detent 46 dropping into the notch 47. The hood is then returned to closed position over the can, when the container being now 115 in horizontal position may be rotated by the crank 18 to sift the ashes. As will be understood, the rotation of the container causes the finer consumed portion of the ashes to drop through the openings or meshes of the 120 side walls 2, whence the same falling upon the auxiliary walls 7, are, due to the inclination of the latter, ejected into the ash can below. Owing to the side walls 44 of the coupling member 24 being of greater length than the sides of the coupling member 23, it will be apparent that the rotary movement of the container will be accompanied 125 by intermittent jars or shocks due to the dropping of the adjacent walls of the mem- 130

ber 24 on the sides of the member 23 as the former successively pass over the center of support. This jarring movement tends to more thoroughly break up the contents of 5 the container and to more completely separate the consumed part of the ashes from the unconsumed and valuable cinders, and has the further effect of facilitating the ejection of the consumed ashes from the 10 auxiliary walls 7. After the ashes have thus been thoroughly sifted, the apparatus will be left to stand undisturbed for a sufficient length of time to permit the dust to thoroughly settle, when the crank may again 15 be given several rapid turns in order to clean the container by dislodging such particles of dust as may have accumulated thereon, whereupon the hood is again opened and the container with the reclaimed 20 cinders therein removed.

It will be understood that the invention is not limited to the embodiment thereof hereinbefore described and illustrated in the accompanying drawings, but it may be embodied in various other forms within the 25 scope of the following claims.

The invention claimed is:—

1. An ash sieving device including a portable ash container in the form of a bucket 30 having foraminous side walls, and outwardly and upwardly diverging protective means outwardly surrounding the side walls to prevent ashes which sift through the side walls from dropping from the container 35 when the latter is in substantially vertical upright position, but adapted to permit such siftings to drop freely from the container arranged to eject the same therefrom when the container is disposed and rotated on a 40 substantially horizontal axis.

2. In an ash sieving device, a portable ash container open at the top and having foraminous side walls and an imperforate bottom, said side walls being outwardly 45 rounded by imperforate outwardly and upwardly diverging auxiliary walls spaced therefrom at the top and abutting said side walls at the bottom and adapted to coöperate with the bottom and side walls for retaining ashes deposited in the container 50 when the latter is in substantially vertical upright position, a removable cover for said container, and rotative supporting and coupling means for detachably mounting said 55 container for rotation on a substantially horizontal axis.

3. In an ash sieving device, a portable ash container in the form of a bucket being open at the top and having an imperforate bottom 60 and foraminous side walls, said side walls being outwardly surrounded by imperforate frusto-cone shaped auxiliary walls abutting said side walls at the bottom and diverging upwardly toward the mouth of the container 65 to form auxiliary container means open at

the top wherein particles of ashes passing through the side walls may be caught and retained when the container is in substantially vertical upright position and wherefrom the ashes may freely drop to be ejected 70 when the container is disposed and rotated in substantially horizontal position, a removable cover for the said container, and rotative supporting and coupling means for detachably mounting said container for rotation on a substantially horizontal axis. 75

4. In an ash sieving device, a portable cylindrical ash container open at the top, and having foraminous side walls and an imperforate flat bottom, imperforate frusto-cone 80 shaped ash retaining walls outwardly surrounding the side walls and diverging upwardly and outwardly from the exterior face thereof and terminating below the mouth of the container, a bail secured to 85 said container, and a removable cover to close the mouth thereof, and rotative supporting and coupling means for detachably mounting said container for rotation on a substantially horizontal axis. 90

5. An ash receiving device including a portable cylindrical ash container open at the top and having foraminous side walls and an imperforate flat bottom, and having a plurality of imperforate shell members 95 surrounding the side walls, said shell members being spaced from the side walls at the top and secured thereto at the bottom and the upper edge of the uppermost of said shell members falling below the mouth of 100 the container.

6. In an ash sieving device, a portable, rotatable ash containing and sieving element, open at one end and closed at the other end, and means for detachably mounting 105 said element for rotation on a substantially horizontal axis, said means comprising a rotatable shaft carrying a coupling member for detachably engaging the closed end of said element and imparting rotative movement thereto, and a detachable revolute member for engaging and supporting the opposite end of said element. 110

7. In an ash sieving device, a portable rotatable ash containing and sieving element 115 of substantially cylindrical form, said element being closed at one end and open at the other end, and means for detachably mounting and rotating said element on a substantially horizontal axis, said means comprising a rotatable shaft carrying a coupling member for supporting the closed end of 120 said element and imparting rotative movement thereto, and a removable, revolute, pivotally mounted cover for closing and supporting the open end of said element.

8. In an ash sieving device, a portable, rotatable ash containing and sieving element, said element being closed at one end and open at the other end, and means for de- 130

- tachably mounting and rotating said element on a substantially horizontal axis, said means including a rotatable shaft carrying a coupling member for detachably engaging and 5 supporting the closed end of said element and imparting rotative movement thereto, a pivot in axial alinement with said shaft and operatively disposed for longitudinal movement relative to the axis of said shaft, a 10 cover for said element loosely mounted for rotary movement on said pivot and adapted to engage the open end of said element, and means for retaining said cover in open and closed positions with relation to said element. 15
9. In an ash sieving device, a portable rotatable ash containing and sieving element, said element being closed at one end and open at the other end, and means for detachably mounting and rotating said element on a substantially horizontal axis, said means including a rotatable shaft carrying a coupling member for detachably engaging and supporting the closed end of said element and imparting rotative movement thereto, a pivot in axial alinement with said shaft and hingedly suspended by an arm for longitudinal movement with relation to the axis of said shaft, a cover for said element 20 loosely mounted for rotary movement on said pivot and adapted to engage the open end of said element, and spring pressed detent means operative on said arm for retaining said cover in open and closed positions with 25 relation to said element.
10. In an ash sieving device, a portable rotatable ash containing and sieving element, said element being closed at one end and open at the other end, and means for detachably mounting and rotating said element on a substantially horizontal axis, said means comprising a short shaft journaled for rotary movement on a horizontal axis and provided at one end with a manually 30 operable crank and carrying at the other end a coupling member adapted to enter and engage a coöoperating coupling member carried by the closed end of said element, said first named coupling member being adapted 35 to freely enter and loosely engage the side walls of said coöoperating member to impart rotary movement to said element, and said coöoperating member having an inwardly extending flange at its outer end for preventing disconnection with the shaft when said element is in horizontal axial position, and a removable revolubly mounted cover for engaging and supporting the open end of said element. 40
11. In an ash sieving device, the combination with an ash can open at the top of a rotatable ash containing and sieving element, and means for detachably mounting said element for rotation over the mouth of said can, said means including a removable hood 45 having side walls and a closed top and adapted to be seated on the upper edge of the can, a shaft journaled for horizontal axial rotation passing through a side wall of the hood and terminating therein, a coupling member carried by the interior end of said shaft and adapted for engagement with the closed end of said sieving element and a crank secured to the exterior end of said shaft, and a head member rotatively disposed within the hood 50 for engaging and supporting the open end of said sieving element. 55
12. In an ash sieving device, the combination with an ash can open at the top, of a rotatable ash containing and sieving element, and means for detachably mounting said element for rotation over the mouth of the can, said means including a hood having side walls and a closed top and adapted to be seated on the upper edge of the can, a bracket disposed within the hood adjacent one of the side walls thereof, a shaft journaled in said bracket and passing through the proximate side wall of the hood and terminating therein, means exterior of the hood 60 for rotating said shaft, and means carried by said shaft within the hood for rotatively and detachably engaging one end of said sieving element, an arm hingedly suspended within the hood from the top thereof, a pivot 65 carried by said arm and extending toward said shaft and in axial alinement therewith, and a head member loosely and rotatably mounted on said pivot for engaging the opposite end of said sieving element. 70
13. In an ash sieving device, the combination with an ash can open at the top, of a rotatable ash containing and sieving element, and means for detachably mounting said element for rotation over the mouth of the can, said means including a hood adapted to be seated on the upper edge of the can, said hood having side walls and a closed top, a U shaped bracket disposed within the hood adjacent one of the side walls thereof, a short shaft journaled in said bracket and passing through the proximate side wall of the hood and terminating therein, a collar on said shaft between the legs of said bracket 75 for preventing longitudinal displacement of the shaft, a crank for rotating the shaft externally of the hood, means carried by the inner end of the shaft for detachably and rotatively engaging one end of said sieving element, a brace diametrically disposed within the hood adjacent the top thereof, an arm hingedly suspended from said brace, a pivot carried by said arm extending toward said shaft and in axial alinement therewith, and a cover plate loosely and rotatably mounted on said pivot for engaging the opposite end of said sieving element. 80
14. In an ash sieving device, the combination with an ash can open at the top, of a hood adapted to cover the can having side 85
15. 16. 17. 18. 19. 20. 21. 22. 23. 24. 25. 26. 27. 28. 29. 30. 31. 32. 33. 34. 35. 36. 37. 38. 39. 40. 41. 42. 43. 44. 45. 46. 47. 48. 49. 50. 51. 52. 53. 54. 55. 56. 57. 58. 59. 60. 61. 62. 63. 64. 65. 66. 67. 68. 69. 70. 71. 72. 73. 74. 75. 76. 77. 78. 79. 80. 81. 82. 83. 84. 85. 86. 87. 88. 89. 90. 91. 92. 93. 94. 95. 96. 97. 98. 99. 100. 101. 102. 103. 104. 105. 106. 107. 108. 109. 110. 111. 112. 113. 114. 115. 116. 117. 118. 119. 120. 121. 122. 123. 124. 125. 126. 127. 128. 129. 130.

walls and a closed top, an interior peripheral flange offset above the lower edge of the hood for engaging the upper edge of the can, means within the hood for detachably and rotatably mounting an ash containing and sieving element therein, and a hinged connection between the can and the hood whereby the latter may be swung upwardly and outwardly to a position which will admit of the insertion of the sieving element within the hood.

15. In an ash sieving device, the combination with an ash can open at the top, of a hood having a closed top and side walls for covering the can, an interior peripheral flange offset above the lower edge of the hood for engaging the upper edge of the can, means within the hood for detachably and rotatably mounting an ash containing and sieving element therein, a hinged connection between the can and the hood whereby the hood may be swung upwardly and outwardly to a given position, and an outstanding arm adjacent said hinged connection for supporting and retaining the hood in such position.

16. In an ash sieving device, the combination with an ash can open at the top, of a hood adapted to cover the can having side walls and a closed top, a peripheral flange adjacent the lower edge of the hood for engaging the upper edge of the can and seating the hood thereon, a portable rotatable ash containing and sieving element adapted to be disposed and carried in vertical upright position, means disposed within the hood for detachably mounting therein said element for rotation in substantially horizontal position, a hinged connection between the can and the hood for raising and turning the hood to a suitable position to permit the introduction of said sieving element and mounting the same therein while said element is in substantially vertical upright position, and a supporting arm carried by the hood for holding the hood in such position.

17. In an ash sieving device, the combination with an ash can open at the top, of a

removable hood adapted to be seated on the upper edge thereof for covering the same, and detachable hinged connecting means between the can and the hood carried by the latter, said means comprising U shaped hook members adapted to be received over the upper edge of the can, outwardly and oppositely extending trunnion members proceeding from the shanks of said hook members, perforated ears depending from the lower edge of said hood through which said trunnion members pass, and a bridge member connecting said trunnion members.

18. In an ash sieving device of the character described, the combination with an ash can open at the top, of a hood adapted to be removably seated on the upper edge thereof for covering the same, and detachable hinged connecting and hood supporting means between the can and the hood, said means being carried by the hood and comprising spaced inverted U shaped hook members adapted to be received over the upper edge of the can, outwardly and oppositely extending trunnion members proceeding horizontally from the shanks of said hood members, perforated ears depending from the lower edge of said hood through which said trunnion members pass, and a bridge member connecting said trunnion members and extending outward substantially at right angles to the axis of the can for supporting the hood when swung backward on the trunnions.

19. In an ash sieving device, of the character described, the combination with a cylindrical ash can open at the top and a hood adapted to be removably seated on the upper edge of the can for covering the same, of a connecting and supporting element carried by the hood adjacent its lower edge for detachably hooking and hinging the hood to the upper edge of the can and for supporting the hood when swung back at right angles to the can, said element being bent up of one continuous piece of rod material.

In testimony whereof I affix my signature.

FRANK H. LEHMAN.
